CLAIM

The ornamental design for a carrying case as shown and described.

DESCRIPTION

FIG. 1 is a front, right and top perspective view of a carrying case, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,
FIG. 10 is another front, right and top perspective view of
the carrying case in a usable state.

The broken lines depict portions of the carrying case that
form no part of the claimed design.

The dot-dash broken lines in FIGS. 1 and 9 depict the
boundaries of the enlargements that form no part of the
claimed design.

1 Claim, 10 Drawing Sheets
